LABEL PASTING AND LIFTING APPARATUS

Paul Arndt, Los Angeles, Calif.

Application June 11, 1935, Serial No. 25,993

22 Claims. (Cl. 216—54)

This invention relates to improvements in apparatus for applying adhesive material to labels and positioning them preparatory to their application upon the articles to be labeled.

5 It is an object of the present invention to provide means mounted for movement upon a label for applying a coating of adhesive material thereto and to lift said label into label removing position by virtue of its adherence to said adhesive applicator; to provide such means for lifting one label at a time from a stack and positioning it for manual removal and application upon an article; and to further provide means for insuring against the removal of more than 10 one label at a time from the stack of labels.

Another object of the invention is to provide in combination with a label pasting and lifting device of the character referred to, a supporting runway for moving the articles into and out of 15 label applying position; to provide means for automatically moving the paste container into label engaging position upon movement of an article away from label applying position; to provide means for automatically admitting an article 20 into label applying position as an article moves therefrom; to further provide means for simultaneously admitting an article to label applying position and operating said paste container; and to still further provide means supported in the 25 path of said articles, which is adapted to be acted upon thereby for causing the movement of said adhesive applicator or container into label engaging position.

Another object of the invention is the provision 30 of spaced paste containers supported for movement onto the marginal edges of a label, there being means for supplying their label engaging surfaces with adhesive material, whereby to apply a coating of adhesive material to the 35 label edges and lift it thereby to label removing position.

A still further object of the invention is to provide a simple and efficient apparatus of the character referred to which may be operated with 40 great rapidity and which will consistently move one label only at a time into position for manual removal and application upon an article.

This invention possesses many other advantages and has other objects which may be made 45 more easily apparent from a consideration of one embodiment thereof. For this purpose I have shown one form in the accompanying drawing and forming part of the present specification. I shall now proceed to describe this form in detail, which illustrates the general principles of 50

my invention; but it is to be understood that this description is not to be taken in a limiting sense, since the scope of the invention is best defined in the appended claims.

In the drawing:

Figure 1 is a rear perspective view of a label pasting and lifting apparatus constructed in accordance with the present invention.

Figure 2 is an end view thereof.

Figure 3 is a longitudinal sectional view taken 10 as indicated by line 3—3 of Figure 2.

Figure 4 is an enlarged, fragmentary bottom plan view taken as indicated by line 4—4 of Figure 2, and

Figure 5 is an enlarged fragmentary view 15 showing the path of movement assumed by the adhesive applying members for assuring the removal of one label only at a time from the label stack.

Referring more in particular to the drawing, 20 a table 10 is shown supported by legs 11. Rails 12 and 13 extend across the table front and provide a track for the articles to be labeled, which in the present instance are shown as being annular containers. Supported on the table behind the 25 track is a stack of labels 14 with their backs facing upwardly.

A feature of the invention resides in applicant's novel means of applying adhesive material to the labels and lifting them to a position where 30 they can be conveniently removed manually by an operator standing in front of the track, for applying them to the containers. In the form of the invention shown in the drawing and hereinafter described, the labels are lifted by the 35 marginal ends, along which the adhesive material is applied in a manner hereinafter fully described.

Referring particularly to Figure 1, a frame is shown comprising front and back members 15 40 16 respectively, connected by end members 17 and 18. The frame is pivotally supported at opposite ends to upright supports 19 and 20 as by bolts 21, shown clearest in Figure 4. The end 17 of the frame has a portion 22 which extends 45 over the labels and forms a supporting arm for a paste container 23. A second arm 24 extends outwardly from the frame end 18 in parallel relationship to the arm 22 and carries a paste container 25 thereon. In order to make possible the 50 handling of labels of different lengths, I show the arm 24 together with its paste container 25 as being adjustable relative to the arm 22 and its paste container 23. The arm 24 is formed with an inwardly extending portion 26 which is se- 55

cured to the front frame member 15 as by bolts 27 and wing nuts 28. A series of openings 29 in the frame member 15 permits for the adjustability of the arm 24 thereon.

5 The paste containers 23 and 25 are similar in construction and are open at their top with a plurality of small capillary outlet openings 30 formed in their bottom as shown clearest in Figures 2 and 4. Applicant prefers to use a thick 10 viscous paste which bleeds or oozes through said outlet openings, forming a coating on the bottom of the paste containers. When the containers are moved into engagement with the marginal ends of the uppermost label said label adheres to 15 the adhesive surfaces of the containers and is lifted into a convenient position where it may be manually removed and applied to an article.

The paste containers 23 and 25 are pivotally mounted on their respective supporting arms 22 20 and 24 in a similar manner, shown clearest in Figure 4. Stub shafts 31 are secured to the paste containers and extend through their supporting arms. They carry wing nuts 32 on their ends with coil spring members 33 interposed between 25 said wing nuts and the supporting arms, whereby the frictional engagement between the paste containers and their supporting arms can be varied through the adjustment of the wing nuts. Each time a label is removed, the height 30 of the label stack is of course reduced and it will be clear how one end of the paste containers will first engage the uppermost label. Through the frictional pivot heretofore described, the paste containers are permitted to automatically adjust 35 themselves upon the marginal ends of the labels. A plurality of holes 34 are provided in the supporting arms 22 and 24 for making possible the interchanging of paste containers to care for labels of different widths. For purposes of production it is desirable to raise the various sized 40 labels to the same label removing position. This is accomplished by maintaining the forward edge of the paste containers in the same position regardless of their length.

45 Paste hoppers 35 and 36 are provided for feeding paste to the respective paste containers 23 and 25, over which they are supported by brackets 37, secured to the upright supports 19 and 20 by bolts 38. As shown clearest in Figure 2, a sliding valve 39 is provided at the mouth of each hopper for controlling the admittance of paste to said paste containers. A member 40 connecting the upper end of the uprights 19 and 20 is provided with a series of openings 40a corresponding to those in the front member 15 of the pivotally mounted frame, whereby to permit a corresponding adjustment of the hopper 36 with the paste container 25.

The means employed by applicant for moving 60 the paste containers into engagement with the label ends, is adapted to be operated by the movement of a labeled container after it has been released by the operator and permitted to roll down the inclined track. A shaft 41 is journaled in 65 bearings 42 mounted on the table legs 11. One end of the shaft extends through its bearing and carries an arm 43, which is connected with the back member 16 of the pivoted frame through a rod 44 which is pivotally connected to said members. The opposite end of the shaft 41 carries an inclined arm 45 which extends upwardly between the rails 12 and 13 in the path of the labeled articles, one of which is shown in Figures 1 and 3 as being about to engage the arm 70 45. The arm is depressed as the article moves

over its projecting end, and the paste containers are swung downwardly into engagement with the uppermost label which adheres thereto. After the article has passed over the extended portion of the arm, the paste containers together with the label are raised to label removing position by coil springs 46, which connect the rear member 16 of the pivoted frame to the table, as shown in Figures 1 and 2. The arm 45 is simultaneously moved upwardly into the path of the labeled articles, to be operated by the next container, after the label has been removed from the paste containers and applied thereto. Stops 47 (Figure 1) are provided for limiting the upward movement of the paste containers. As a means of adjustment to balance the apparatus under varying conditions, I provide a turnbuckle 48 between the coil springs 46.

The objection to lifting more than one label at a time is overcome by moving the paste containers away from the label stack in an arc. The supporting frame for the paste containers is pivoted sufficiently above the top of the label stack to cause the containers to swing outwardly as they start to swing upwardly away from the stack 25 of labels. The top label adhering to the paste containers, is accordingly slid forward slightly relative to the adjacent label therebeneath as shown in Figure 5 and its forward end is raised first, thereby breaking the vacuum created between the two sheets. In order to further facilitate the separation of the uppermost sheet from the adjacent sheet therebeneath, I provide the inner faces of the label guides 49 and particularly the front one, with roughened or file-like surfaces 50. As the top label is moved forward and upward, its front edge engages and is dragged over the roughened surface of the front guide as shown in Figure 5, thereby insuring its separation from the next and adjacent label.

Figures 2 and 3 best show the means employed by applicant for automatically releasing one unlabeled can at a time, to permit its movement into label applying position. An arm 51 is secured to the shaft 41 adjacent the arm 45. It is connected through a rod 52, to the vertical arm 53 of an angled member which is pivotally connected as at 54 to a supporting bracket 55 mounted on the underside of the table 10. A rod 56 is pivotally connected as at 57 to the horizontal arm 58 of the angle member and extends upwardly through a sleeve 59 into the path of the unlabeled containers for normally restraining them from moving down the inclined track into label applying position. Figure 3 shows a number of such unlabeled cans in dotted lines. When the arm 45 is depressed as by the passing of a labeled article over its extended end, it will be clear from the foregoing description now the rod 56 is retracted and an unlabeled container released to roll into label applying position in front of the label stack.

In operation the operator picks a label from the label stack and applies it to an article which is then given a roll down the inclined track. As the article moves over the extended end of the arm 45 said arm is depressed and the paste containers are moved downwardly onto the marginal ends of the uppermost label of the stack. The pin 56 is simultaneously retracted to release an unlabeled article for rolling movement into label applying position. After the labeled article has passed over the extended end of the arm 45 the paste containers are moved upwardly by the spring members 46 and lift the uppermost label by its

ends, which adhere to the bottom of said paste containers. At the same time the pin 56 is moved upwardly to prevent more than the one unlabeled article from moving into label applying position 5 and the arm 45 is raised to normal position. The label is pulled from the undersides of the paste containers by grasping its forward edge and is turned over upon the surface of the unlabeled article which is then rolled down the track and 10 over the arm 45 for releasing the next unlabeled article and picking up a label to be applied thereto in the manner described.

I claim:

1. In an apparatus of the character described, 15 a movably supported container for adhesive matter, the bottom thereof being adapted to allow said matter to ooze therethrough, means for supporting labels in stacked form, said container being adapted to move down upon the top label to 20 apply said adhesive matter thereto and to lift said label from the stack for application upon an article, conveying means for the articles, and operating connections between said conveying means and said container which are adapted to 25 be acted upon during the movement of an article for effecting the operation of said container.

2. In an apparatus of the character described, 30 a movably supported container for adhesive matter, the bottom thereof being adapted to allow said matter to ooze therethrough, means for supporting labels in stacked form, said container being movable down upon the top label to apply said adhesive matter thereto and to lift said label from the stack, whereby it can be manually removed 35 from said container and applied to an article, means forming a supporting runway for moving articles into and out of label applying position, and means supported in the path of the articles which is adapted to be acted upon by an article 40 for operating said container.

3. In an apparatus of the character described, 45 a movably supported container for adhesive matter, the bottom thereof being adapted to allow said matter to ooze therethrough, means for supporting labels in stacked form, said container being movable down upon the top label to apply said adhesive matter thereto and up to lift said label from the stack to a position convenient to the article to be labeled, means for directing the articles into and out of label applying position, and means adapted to be operated during the movement of an article away from label applying position for actuating said container.

4. In an apparatus of the character described, 55 a movably supported container for adhesive matter, the bottom thereof being adapted to allow said matter to ooze therethrough, means for supporting labels in stacked form, said container being movable down upon the top label to apply said adhesive matter thereto and up to lift said label from the stack, whereupon it can be manually removed from said container and applied to an article, means forming a supporting runway for moving articles into and out of label applying position, and means operable upon the movement of an article away from label applying position for operating said paste container to pick up another label and simultaneously release another article for movement into label applying position.

5. In an apparatus of the character described, 65 means for supporting labels in stacked form, spaced paste containers supported for simultaneous movement toward and away from said label stack with means formed in their label engaging sides for permitting paste to ooze there-

through, said containers being movable down upon the marginal edges of the top label to apply paste thereto and upwardly to lift said label from the stack by its edges, whereby it can be manually removed from said container and applied to an 70 article, means forming a supporting runway for the articles, and means supported in the path of said articles which is adapted to be acted upon by one of said articles for causing the operation of said paste container.

6. In an apparatus of the character described, 75 means for supporting labels in stacked form, spaced paste containers supported for simultaneous movement toward and away from said label stack with means formed in their label engaging sides for permitting paste to ooze therethrough, said containers being movable down upon the marginal edges of the top label to apply paste thereto and upwardly to lift said label from the stack by its edges, whereby it can be 80 manually removed from said container and applied to an article, means forming a supporting runway for the articles, a member supported in the path of said articles, and means connecting said member with said paste containers, whereupon the movement of an article into engagement with said member causes the containers to move 85 into engagement with the top label.

7. In an apparatus of the character described, 90 means for supporting labels in stacked form, an arm supported for swinging movement, a paste container having a label engaging side with openings therein through which paste is adapted to ooze, means yieldingly supporting said container on said arm to permit bodily movement 95 thereof, and means acting on said arm to move said container onto the uppermost label of said stack for applying paste thereto, the removal of said container operating to lift said label.

8. In an apparatus of the character described, 100 means for supporting labels in stacked form, an arm supported for swinging movement, a paste container carried by said arm and having a label engaging side with openings therein through which paste is adapted to ooze, means forming a 105 supporting runway for the articles to be labeled, a member supported in the path of the articles, and operating connections from said member to said arm, said member being adapted to be acted upon by an article for causing the movement of 110 the paste container onto the top label of said stack.

9. In an apparatus of the character described, 115 means for supporting labels in stacked form, an arm supported for swinging movement, a paste 120 container carried by said arm and having a label engaging side with openings therein through which paste is adapted to ooze, said container being movable down upon the top label to apply paste thereto and to lift said label from the stack, means forming a supporting runway for moving 125 articles into and out of label applying position, means responsive to the movement of an article away from label applying position and effecting a movement of said paste container onto a label, 130 and means for admitting an article to label applying position.

10. In an apparatus of the character described, 135 means for supporting labels in stacked form, a label selecting device, means supporting said device for swinging movement toward and away from said stack, said selecting device including a pair of label engaging means for acting upon the opposite edges of the uppermost label and adapted to remove the same from the stack when 140

said selecting device is moved away from the same, the swinging movement of said label selecting device from the label stack causing the uppermost label to be lifted in an arcuate path 5 from engagement with the next adjacent label, whereby to effect a separation of said labels and eliminate the possibility of removing more than one label at a time from the stack.

11. In an apparatus of the character described, 10 means for supporting labels in stacked form, a label selecting device supported for movement toward and away from said label stack, and having means associated therewith for acting upon and removing a label from said stack for application 15 upon an article, means for supporting an article in a label applying position, and means responsive to the movement of an article away from label applying position for actuating said label selecting device.

12. In an apparatus of the character described, 20 means for supporting labels in stack form, a label selecting device supported for movement toward and away from said label stack and having means associated therewith for acting upon and removing a label from said stack for application 25 upon an article, means forming a support for articles moving into and out of label applying position, means adapted to be operated upon the movement of an article away from label applying 30 position for actuating said label selecting device, and means for admitting another article to label applying position.

13. In an apparatus of the character described, 35 means for supporting labels in stack form, a label selecting device supported for movement toward and away from said label stack and having means associated therewith for acting upon and removing the uppermost label from said stack for application upon an article, conveying means for 40 the articles, and means adapted to be acted upon by a moving article for actuating said label selecting device.

14. In an apparatus of the character described, 45 means for supporting labels in stacked form, a label selecting device supported for movement toward and away from said label stack and having means associated therewith for acting upon and removing a label from said stack for application 50 upon an article, conveying means for moving articles into and out of label applying position, and means adapted to be actuated upon by the movement of an article away from label applying position for operating said label selecting device and causing the movement of another article into label applying position.

15. In an apparatus of the character described, 55 means for supporting labels in stack form, a label selecting device, means for supporting said device for swinging movement toward and away from said label stack, said selecting device including a pair of adhesive applying label engaging surfaces positioned a fixed distance apart for acting upon the marginal edges of a label to lift the same when said selecting device is removing from the label stack, the swinging movement of said selecting device from the stack causing the uppermost label to be lifted in an arcuate path from engagement with the next adjacent label, whereby to effect a separation of said labels and eliminate the possibility of removing more than one label at a time from the stack.

16. A label selecting device comprising a member having a label engaging surface with means associated therewith for causing the adherence of 75 a label thereto, a swinging support for said mem-

ber, means for yieldingly mounting said member on its support for bodily rotative movement with respect thereto, means for supporting labels in stack form, and means for acting on said swinging support for causing the movement of said label engaging surface onto the uppermost label, the yieldability of said yieldably mounted member acting to ensure the complete engagement of the label engaging surfaces with said label. 5

17. In an apparatus of the character described, 10 a pair of containers for adhesive matter, the bottoms thereof being adapted to allow said matter to ooze therethrough, means for supporting labels in stacked form, and means for supporting said containers for movement down upon the edges 15 of the top label to apply said adhesive matter thereto and to lift said label by its edges in an arcuate path from engagement with the adjacent label therebeneath.

18. In an apparatus of the character referred 20 to, supporting means, a pair of paste containers, means for yieldably mounting said containers on said supporting means to permit bodily movement relative thereto, the bottoms of said containers being provided with small orifices to permit said 25 adhesive matter to ooze therethrough to the label engaging surfaces thereof, means for supporting labels in position to receive said containers thereupon for applying adhesive matter thereto, said supporting means including means for causing 30 said containers to lift the uppermost label in an arcuate path from engagement with the adjacent label therebeneath.

19. In an apparatus of the character described, 35 means for supporting labels in stacked form, a paste container, means for supporting said container for swinging movement toward and away from said stack of labels about a fixed pivot, said paste container having means formed in its label engaging side for permitting paste to ooze 40 therethrough onto its label engaging surface, a paste reservoir with means associated therewith for controlling the admittance of paste to said paste container, and means for moving said container into engagement with the uppermost label 45 which adheres to the label engaging surface, said label being lifted in an arcuate path from engagement with the adjacent label therebeneath when the paste container is swung away from the label stack. 50

20. In an apparatus of the character described, 55 means for supporting labels in stacked form, a paste container, means for supporting said container for swinging movement toward and away from said stack of labels about a fixed pivot, said paste container having means formed in its label engaging side for permitting paste to ooze there- 60 through onto its label engaging surface, and means for moving said container into engagement with the uppermost label which adheres to the label engaging surface, whereupon the swinging movement of the container away from said stack and about its pivot lifts the uppermost label in an arcuate path from engagement with the adjacent label therebeneath. 65

21. In an apparatus of the character described, 70 means for supporting labels in stacked form, a pair of members positioned in spaced relationship a fixed distance apart, means for supporting said members for movement toward and away from said label supporting means, said means including adhesive surfaces for movement onto the marginal edges of the labels, means for moving said members toward the top label of said stack, said label being removed from said stack in a 75

lateral direction by engagement with said surfaces and by movement of said member supporting means away from said label supporting means.

22. In an apparatus of the character described, means for supporting labels in stacked form, a label selecting device, means supporting said device for movement about a pivot disposed to one

side of a plane including the outermost label of said stack, said selecting device including label engaging means adapted for action upon said outermost label to lift it in an arcuate path about said pivot.

5

PAUL ARNDT.
